WEB SUPPLY CARRIER FOR TYPEWRITING MACHINES

Charles Willis Larkin, Brooklyn, N. Y., assignor,
by mesne assignments, to American Sales Book
Company, Inc., a corporation of Delaware

Application March 31, 1931, Serial No. 526,592

24 Claims. (Cl. 197—133)

This invention relates, in general, to recording machines, such as typewriting machines, adding machines provided with printing mechanism, and the like, and with respect to its more specific 5 features, to apparatus for the control and disposition of the continuous or long strips of supply paper frequently used in such machines.

Among the objects of the invention is the provision of practical and efficient instrumentalities for effecting various improved results, as for instance, wherewith long, continuous, paper strips supplied to the machines mentioned may be shifted laterally in unison with the lateral shift of the paper feed devices so as, as much as possible, to avoid fanning or lateral shift of the superposed paper supply strips relative to each other; wherewith the container and the guides for the paper supply may readily and quickly be detached from the recording machine when it is not desired to use it; wherewith the force of the shock or recoil due to forcible movements of the paper-shifting devices, or to a great weight of supply paper, is cushioned, or these effects absorbed in a gradual manner so as not injuriously 25 to shock and vibrate the machine; wherewith the injurious or shock effect of the operator's violently thrusting the paper carriage of a typewriting machine to the right in preparation for writing a new line is minimized, if not entirely eliminated; wherewith the guiding of the paper from the supply point to the typewriting machine is facilitated and rendered more practical, and wherewith the paper supply container is adapted to accommodate paper supplies of various different widths. Withal, the object includes the provision of a simple and inexpensive construction of apparatus, which will be strong and rugged, preferably all parts being of metal.

Other objects of the invention will in part be 40 obvious and will in part appear hereinafter.

The invention accordingly comprises the features of construction, combinations of elements, and arrangement of parts, which will be exemplified in the construction hereinafter set forth and the scope of the application of which will be indicated in the claims.

For a fuller understanding of the nature and objects of the invention, reference should be had to the following detailed description taken in connection with the accompanying drawings, in which:

Fig. 1 is a side elevation illustrating an embodiment of the invention, the paper supply container being shown associated with a type-writing machine of standard construction, said

machine being illustrated in a diagrammatic manner;

Fig. 2 is a plan view of Fig. 1, the platen of the typewriting machine being shown more in detail, and a part of the keyboard also appearing; 5

Fig. 3 is an enlarged, side view, partly in section, of the paper supply container and its associated supports and shifting devices, as appearing at the right in Fig. 1;

Fig. 4 is a plan view of a detail of Fig. 3, showing one of the rails and its associated anti-friction rollers;

Fig. 5 is a fragmentary view looking at the left of Fig. 3, and illustrating the actuating block which is mounted on the container, and through which shift movement is imparted to the container; and

Fig. 6 is a plan view illustrating paper guides, or brackets, one of which is disposed at each end of the receiving compartment of the supply container; 20

Fig. 7 is a perspective view partially fragmentary of the device as assembled.

Referring now more specifically to the drawings, it is observed that the supply-controlling 25 devices are suitable for use with various machines, but are herein illustrated in connection with a standard form of typewriting machine, the frame of this latter machine being generally indicated by the numeral 1. The numeral 2 indicates the platen carriage which is shiftable in letter-spacing direction, as usual in typewriting machines, and the numeral 3 indicates the platen journaled in the platen support 4, this support being reciprocally shiftable up and down, that 30 is, in case-changing direction, by use of the shift key 5 of the keyboard. The platen support 4 is mounted on the platen carriage 6, and the up and down shift of the platen is effected through the instrumentality of the usual lift hooks 7 (only 40 one of which is shown), which are actuated from the key 5 through the lift-hook rod 8. All these parts may be as usually appear in standard Underwood typewriters and need not be further described. 45

Referring to Fig. 1, the record paper to be written upon by the machine is illustrated at 9. This paper may consist of a single, long, continuous strip, zigzag folded so as to form a compact supply pack, as indicated at 10, from which pack the 50 paper strip is led beneath the platen of the typewriting machine. But it is to be understood that the supply may consist of a number of superposed record strips, with or without long, continuous, carbon strips. When a plurality of the 55

continuous strips, including continuous carbon strips, is employed, their advance ends are entered beneath the platen and coact therewith to be fed in line-spacing direction by rotation of the platen. In so far as the manipulations by the typist are concerned, it is to be understood that the operations of typing and of line-spacing, and of letter-spacing and shifting the platen and the platen carriage, are similar to standard practice, and may be as exhibited in standard typewriting machines, or as exhibited in other recording machines.

At the rear of the typewriting machine is the paper-shifter member generally indicated by the letter A. This paper-shifter member is mounted for reciprocal shift movement in letter-spacing direction and, in the embodiment illustrated, includes a paper container, receptacle or supply container, into which the supply of paper may be introduced, as illustrated in Fig. 1. Specifically, in the present embodiment, the paper-shifter member includes a shiftable carrier frame of cradle-like design. In the embodiment illustrated, this carrier-frame is composed of two parallel angle bars 15 and 16, connected by cross bars 17 and 18, to form a skeleton, cradle-like frame. Affixed to this carrier-frame is the paper container proper which, in the embodiment illustrated, is of generally U-shape, and is formed of foraminous material.

Referring to Fig. 3, the paper container is made of light, perforated sheet metal, bent in a generally U-shape, to form the bottom wall 19 and the side walls 20 and 21 integral with the bottom wall. This U-shaped container is removably fixed to the bars 15 and 16 by the screws 22. In order that the paper container may accommodate supply paper strips of various different widths, and indeed widths which are even wider than the longitudinal dimension of the U-shaped container, the opposite ends of the container may be left open, and the paper guides 23 may be disposed at the opposite ends of the container. These guides consist of guide bars 23, each having a handle 24 and two legs 25. These bars 23 are mounted between the limbs, or sides, 20 and 21 of the U-shaped container, and are adjustable toward and from each other. To this end, the sides 20 and 21 of the container are slotted as indicated at 26, and the guides 23 are supported on the container by screws 27 passing through the slots 26. Light plate springs 28 intervene the heads of the screws 27 and the container wall to develop some friction and prevent rattling. After the bars 23 have been adjusted to the desired position, they may be firmly secured in place by the thumb screw 29. These bars 23 serve not only to guide the paper strip coming from the container, as illustrated, for instance, in Fig. 1, but they may be adjusted so as to dispose the supply of paper more to one side of the center of the container than to the other, or vice versa. The distance between the opposite guide bars 23 may be adjusted to less than the length of the U-shaped walls, or they may be disposed a greater distance apart to accommodate supplies of such a width as to project through the opposite, open ends of the container.

Beneath the paper container is a base frame along which the container shifts. This base frame may rest upon the table, or other surface, alongside the typewriting machine, and ordinarily will be firmly secured at the rear of the typewriting machine. Like the container

carrier above described, the base frame is composed of two parallel angle bars 30 and 31, having their arms upwardly inclining and diverging from the apices and connected by several cross bars 32, 33 and 34, to form a skeleton, cradle-like base frame, in which the paper container is received and supported for being shifted in letter-spacing direction and in unison with the platen of a typewriter. For directly supporting the paper container in the base frame, anti-friction roller bearings, engaging rails or tracks, are employed.

In the embodiment illustrated, there are upper and lower parallel rails, the same being fastened to the base frame, one of these rails being the cylindrical bar 32 which forms a portion of the base frame, as hereinbefore mentioned. The other rail is a similar cylindrical bar 35 and is secured in position above the bar 34 of the base frame. The anti-friction bearings are mounted upon the container, being directly connected to the carrier frame 16, which forms a portion of the container. As illustrated, one anti-friction roller bearing 36 is journaled on a stud 37, secured to an angle plate 38, slideable to different adjusted positions beneath the carrier frame bar 17, and securable in adjusted position by a clamping screw 39. Alongside the bearing roller 36 is another anti-friction roller 40 journaled on a stud 41 depending from a U-shaped bracket 42, the legs of this bracket being slideable to different adjusted positions on the carrier frame member 17, and being secured by screws 43. A number of anti-friction, roller-bearing units, each including a roller 36 and a roller 40, may be utilized at a number of points in the length of the container, the respective rollers in each unit being disposed at different points circumferentially of the rail 35, the roller 36 taking the vertical thrust of the weight of the container, the roller 40 being adapted to take any lateral thrust that may be developed.

For supporting the container on the upper rail 32, each angle bar 15 and 16 has a stud 44 on which a bearing roller 45 is journaled, these rollers each having annular grooves more or less intercepted by the circumference of the track rail 32, so as to have some resistance against relative lateral displacement on the rail.

It will be understood that the paper container and its carrier frame provide a paper-shifter member which is reciprocally shiftable in the base frame, the anti-friction bearing rollers shifting with the container and running against the several rails mentioned.

When the supply of record paper to be inscribed consists of a number of long, continuous strips in superposed relation and proceeding from a source of supply such as a roll, or a zigzag pack, to the feed device or platen of the recording machine, there is a tendency for the different strips to be displaced laterally, more or less, from each other, with the result that the printed forms of different superposed strips will be so much out of registry at the printing point that the inscription on the duplicates will not correspond in position on the printed form with the inscription on the original. This departure from registration tends to increase the greater the number of superposed strips employed.

Not only does this tendency to lateral displacement pertain to long, continuous strips by reason of the intervening reach of strip material between the bulk of the supply and the typewriting machine. The movement of the paper feed

mechanism or platen of the recording machine in a letter-spacing direction, whether during the typing operation or upon the return of the platen in preparation for writing a new line, has the effect of twisting or prejudicially folding the continuous strips with consequent displacement therebetween, so that but little reliance upon the paper being fed in predetermined lines can be expected. On the contrary, the different strips 10 of paper are displaced laterally from each other to a considerable extent. To the end of avoiding these objections as much as possible, and of improving registration at the printing point of superposed printed forms and of having the strips 15 feed along predetermined lines, the present invention provides for shifting the paper strips in letter-spacing direction in unison with the platen of the machine, and it also provides for, as far as possible, avoiding relative displacement of 20 different superposed paper strips, and possible injury or deleterious effect upon the machine or the printing by a substantial weight of the paper supply being used.

Between the platen carriage of the typewriting 25 machine and the paper-shifter member hereinbefore mentioned, there are operative connections whereby shift of the platen carriage in letter-spacing direction causes shift of the paper container, or paper-shifter member, in unison therewith. In the present embodiment an actuating member, or block, 50 is coupled to the paper container and has shift movement relative to said container. As illustrated, the block 50 is mounted on a backing plate 51 fixed on the side wall 20 30 of the bent, foraminous plate composing the container proper. Projecting from the base plate 51 are two pins 52 and 53, preferably screws. Said actuating block 50 is of angular shape and has a flat portion 54 bearing against the base plate 51 and having a slot 55 through which the pins 35 52 and 53 loosely pass. Said pins have heads for retaining the actuating block 50 against the base plate 51. Also, plate 50 has an opening, throat, or recess, 57, for being coupled or engaged 40 with a block-driving member 58, hereinafter more particularly described.

Directly connected to be shifted in letter-spacing direction with the platen of the typewriting machine, is a connecting rod 59 which is directly 45 supported by the platen carriage and extends in letter-spacing direction. The block-driving member 58 consists of an arm, one end of which is sleeved for longitudinal adjustment along the connecting rod 59, the other end of this arm being free for being loosely coupled to the actuating block 50 by entering the opening 57 in such block. A clamping screw 60 is utilized for securing the block-driving arm 58 in different adjusted 50 positions on the connecting rod 59. For securing the connecting rod 59 to the platen carriage, two similar arms 61 are provided (only one of which is shown). Each of these arms has a split coupling 62, by means of which it may be securely fastened to the split collar (of the platen carriage), in which the lift hook rod 8 is journaled. It may be noted at this point that the actuating devices coupling the container for reciprocal shift movement in letter-spacing direction by actuation of the platen carriage are connected 65 to the platen carriage independently of the up and down case-shifting movement of the platen; that is, independently of platen shift which effects change from capitals to small letters, and the like. Any device for coupling the connecting rod 59 to the platen carriage, and which per-

mits independent, vertical shift of the platen, is within the purview of this part of the invention.

It will now be understood that as the platen shifts in letter-spacing direction, the connecting rod 59, and the block-shifting arm 58, shift in 5 unison therewith and impart shift movement in letter-spacing direction to the actuating block 50, which latter, in turn, is adapted to communicate similar shift to the container in which the bulk supply of paper is placed. 10

This invention provides for cushioning movement, especially the final movements, of the paper container, and for lessening the shock on the platen carriage due to the paper container, which latter may be rather heavily weighted by 15 reason of the bulk of supply paper therein. A device is provided which is adapted resiliently to arrest shift movement of the container at the end of its stroke, and which also cooperates to restrain relative movement between the paper container and the actuating block 50. To these and other ends, a spring 65 is interposed between the paper container and the block 50. As illustrated, this spring is helical, one end being fast to the block 50 and the other end to the backing plate 51 20 on the container wall, the block 50 and container being thus resiliently but positively connected to each other.

It will also be observed that the extent of shift of the paper container, after arrest of its actuating mechanism, is limited. When the block-shifting arm 58 is arrested by arrest of the connecting rod 59 on the return stroke of the platen carriage, further movement of the container is gradually checked by the spring 65. If the spring 35 65 does not alone stop this further movement, the pin 52 will do so by abutting the end of slot 55 in the block 50, the end of the slot acting as a stop.

At the upper part of the side wall 20 of the container is a table on which the supply paper strips are supported as they pass to the platen. This table consists of a swinging plate 70, hinged at 71 to the side wall 20 and having legs 72 which may rest on the connecting rod 59 for supporting the paper table 70 in elevated position. The 45 paper table 70 may be of foraminous material forming a hinged flap of the side wall 20, although other material may be used. In superposed relation to the paper table are the lateral paper guides 73, the same being plates adjustable to different positions along the flap or table 70. The guides 73 are strung on rod 74, which latter is supported at its ends in ears or brackets 75. The brackets 75 and the legs 72 may be integral parts of a plate 76 secured to the underside of the table 55 70 by a series of screws 77.

For steadyng the paper container on the base frame, the carrier frame may be provided with one or more channel plates 78 secured at intervals to the underside of cross bar 17, the rail 35 60 lying partly in these channels.

For detachably securing the base frame to the typewriter or other machine, various different securing devices may be utilized. As herein illustrated, sleeves or clevises 79 are engaged over 65 frame member 80 of the typewriter, and secured in place by clamp screws 81. Each side bar 30 and 31 of the base frame terminates in a standard or leg 82, having a slot 83, the leg being clamped in adjusted position to clevises 79 by 70 separate clamp plate 84 and clamping screw 85. At 86 is a rubber foot or shoe for supporting the central portion of the base frame.

Whereas a container for receiving the supply of paper in bulk, as in a flat packet 10, from 75

which the strips may be led to the platen, or other paper-feeding or paper-printing device, has been described, it is to be understood that certain broader features of the invention contemplate the shifting laterally of the paper strips in unison with the platen without the paper strips being disposed in a container. As to those features, it might be desirable to shift only reaches of strip between the platen and the supply pack, in which case the bulk of supply might rest in stationary position in rear of the typewriter.

The operation of the device will be largely obvious from the foregoing description, but brief reference thereto may be made.

It will be apparent that the base frame of the paper supply apparatus may readily be attached and detached from the typewriting machine by merely manipulating the screws 81 and 85. It will also be perceived that by reason of the cradle-like shape of the base frame and the container, these two parts may be closely nested, the container in the base frame, so as to take up relatively small vertical space. Also, inasmuch as the cradle-like container is largely suspended from the two tracks 32 and 35, the center of gravity of the container, and its load of supply, is relatively low and the apparatus thus rendered stable in marked degree. It will also be seen that the container including its carrier frame may be readily removed from the base frame without any complicated manipulation, it being required only to disengage the block-driving arm 58 from the actuating block 50. Having placed a supply of zigzag folded paper strips "en bloc" in the foraminous container, as illustrated in Fig. 1, the advance ends of the paper strips are led across the paper table 70 and assembled in operative feed relation with the platen 3. As typing progresses, the platen is shifted to the left by the mechanism 40 of the typewriting machine. In unison therewith, and through the actuating members 61, 59, 58, 57 and spring 65, the container with its paper supply also is shifted to the left, moving easily in letter-spacing direction along the rails 32 and 35. It will be noted that shift movement is imparted to the container through the spring 65, the shift actuation of the block 50 tending to elongate this spring. Ordinarily, a spring 65 may be used which, when the apparatus is at rest, will cause the pin 53 to be in abutting relation with the end of the slot 55. Upon quickly thrusting the platen carriage to the right, as is usual in preparation for beginning a line of writing, the platen carriage will be positively arrested by the right-hand margin stop of the typewriter; also, the block-driving arm 58 will be as promptly arrested inasmuch as it is positively connected to the platen carriage.

But the container with its supply of paper strip may have a further movement to the right, which movement will gradually be checked by the spring 65, and ultimately stopped by contact of the pin 52 with the end of the slot 55. Inasmuch as the load due to the paper container and the supply therein may be comparatively heavy, so as to have considerable momentum on its return movement just mentioned, it is very desirable yieldingly to bring the paper carriage to rest, as by the spring 65, in order that the shock otherwise resultant from sudden arrest of this heavy load may not be imparted to the platen and platen-carrying parts of the typewriting machine. Furthermore, by bringing the paper container gradually to rest, the paper supply and the reaches thereof extending from the container

to the platen are not stopped suddenly. Consequently, lateral registration of the different superposed paper strips is not apt to be disturbed.

By providing the paper container walls with numerous round perforations, guide pins and aligning pins may be readily distributed at various different points for the purpose of guiding paper strips of different widths, and the like. In Fig. 7, the numerals 90 indicate guide pins supported in the apertures of the paper table 70. The container is adapted for utilizing any practical width of paper that it is sought to use. Ordinarily, the container will be of a suitable size to accommodate paper of standard width for standard width platens. However, the container will readily accommodate widths of paper which overlap the open ends of the container, this wider paper being steadied and retained by the paper guides 23. The paper guides 23 may be shifted along the paper table 70 to accommodate different widths of paper. It is observed that for supporting the paper table 70, no part of the typewriting machine is required. Once the connecting rod 59 is secured in place, the paper table 70 may be upheld by the legs 72 resting upon this rod.

It is observed that roller 40 is slightly below the level of the center of rail 35 and underlies said rail to a small extent, when the container is suspended on the rails. Hence, rise of the container of the rail 35 is somewhat resisted by the underlying roller 40. But due to resiliency of the bracket 42, the roller 40 may be sprung past the rail when desired.

Since certain changes may be made in the above construction and different embodiments of the invention could be made without departing from the scope thereof, it is intended that all matter contained in the above description or shown in the accompanying drawings shall be interpreted as illustrative and not in a limiting sense.

Having described my invention, what I claim as new and desire to secure by Letters Patent is:

1. In an apparatus of the character described, in combination, a paper-shifter member mounted for reciprocal shift movement, a reciprocally shiftable actuator to which said member is operatively connected for being shifted, the operative connection between said member and actuator including an actuating block having one or more slots, pins on said member loosely engaging said slot or slots so as to mount the block for longitudinal translatory sliding movement upon said member substantially in the direction of shift thereof, said block having an opening for engagement by a block-driving member, and a spring cooperable to restrain movement between said shifter-member and said block in one direction.

2. In an apparatus of the character described, in combination, a paper-shifter member mounted for reciprocal shift movement, a reciprocally shiftable actuator to which said member is operatively connected for being shifted, the operative connection between said member and actuator including a connecting rod supported on, and shiftable with, said actuator, a driving arm adjustably fixed to said connecting rod, a block coupled to said arm for being reciprocally shifted by said arm, said block being coupled to said shifter-member for shift movements relative to the latter, the coupling means between said block and shifter-member including a spring operatively connecting said block and shifter-member to restrain relative movement thereof, and stops

engageable with each other upon shift movements in opposite directions of the block for limiting the extent of relative opposite shift movements between said block and shifter-member.

5. 3. In an apparatus of the character described, in combination, a rail, a paper container shiftable on said rail, anti-friction rollers bearing on said rail, a U-shaped bracket supporting one of said rollers and having its legs slidable to different 5 adjusted positions on said container, and an angle plate supporting another of said rollers and slideable to different adjusted positions on said container.

4. In an apparatus of the character described, 15 in combination, a shiftable paper container of generally U-shape, the limbs of the U having slots, one or more paper guides adjustable in the line of shift, and means passing through said slots to secure said guides in adjusted position.

20. 5. In an apparatus of the character described, in combination, a shiftable paper container having a wall of foraminous material, one of said walls including a hinged flap cooperable as a paper support.

25. 6. In an apparatus of the character described, in combination, a shiftable paper container having a wall of foraminous material, one of said walls including a hinged flap cooperable as a paper support, and paper guides above, and adjustable along, said flap, said flap having supporting legs.

30. 7. In an apparatus of the character described, in combination, a shiftable paper container of generally U-shape, one of the limbs of the U having a hinged flap provided with supporting legs, 35 and paper guides adjustable to different positions along said flap.

8. In an apparatus of the character described, in combination, a shiftable paper container of generally U-shape, one of the limbs of the U having a hinged flap provided with supporting 40 legs, and paper guides adjustable to different positions along said flap, one of the limbs of said container being of foraminous material.

9. In an apparatus of the character described, 45 in combination, a shiftable paper container of generally U-shape, one of the limbs of the U having a hinged flap provided with supporting legs, and paper guides adjustable to different positions along said flap, one of the limbs of said container being of foraminous material, and a shiftable carrier frame to which said container is affixed.

10. In an apparatus of the character described, 50 in combination, a shiftable paper container of generally U-shape, one of the limbs of the U having a hinged flap provided with supporting legs, paper guides adjustable to different positions along said flap, one of the limbs of said container being of foraminous material, a shiftable carrier frame to which said container is affixed, and a base frame having rails on which said carrier frame shifts.

11. In an apparatus of the character described, 55 in combination, a shiftable paper container of generally U-shape, one of the limbs of the U having a hinged flap provided with supporting legs, paper guides adjustable to different positions along said flap, one of the limbs of said container being of foraminous material, a shiftable carrier frame to which said container is affixed, a base frame having rails on which said carrier frame shifts, and anti-friction bearings between said carrier frame and said rails.

12. In an apparatus of the character described, 60 in combination, a shiftable paper container of

generally U-shape, one of the limbs of the U having a hinged flap provided with supporting legs, paper guides adjustable to different positions along said flap, one of the limbs of said container being of foraminous material, a shiftable carrier frame 5 to which said container is affixed, a base frame having rails on which said carrier frame shifts, anti-friction bearings between said carrier frame and said rails, and means adapted detachably to clamp said base frame to a recording, or other, 10 machine.

13. In an apparatus of the character described, in combination, a shiftable paper container of generally U-shape, one of the limbs of the U having a hinged flap provided with supporting 15 legs, paper guides adjustable to different positions along said flap, one of the limbs of said container being of foraminous material, a shiftable carrier frame to which said container is affixed, a base frame having rails on which said 20 carrier frame shifts, anti-friction bearings between said carrier frame and said rails, and means adapted detachably to clamp said base frame to a recording, or other, machine, said base frame 25 having a rubber supporting foot.

14. In a supply carrier for writing machines, in combination, a base frame composed of parallel, angle bars having upwardly inclining arms diverging from their apices and being connected by cross-bars to form a skeleton, cradle-like frame, a 30 cradle-like carrier frame having supports at points spaced outwardly and upwardly from said apices and being shiftable on its supports in said base frame and having walls to provide a paper container.

15. In an apparatus of the character described, in combination, a base frame composed of parallel, angle bars connected by cross-bars to form a skeleton, cradle-like frame, and a cradle-like carrier frame shiftable in said base frame and having 40 walls of foraminous material to provide a paper container, the opposite ends of said container being open, and paper guides extending across the open ends of said container and adjustable toward and from each other.

16. In an apparatus of the character described, in combination, a base frame composed of parallel, angle bars connected by cross-bars to form a skeleton, cradle-like frame, a cradle-like carrier frame shiftable in said base frame and having 50 walls of foraminous material to provide a paper container, the opposite ends of said container being open, paper guides extending across the open ends of said container and adjustable toward and from each other, a shifter block carried by said 55 paper container and reciprocal thereon, means to limit the extent of reciprocal movement between said block and container, and a spring connecting said block to said container.

17. In an apparatus of the character described, 60 in combination, a base frame composed of parallel, angle bars connected by cross-bars to form a skeleton, cradle-like frame, a cradle-like carrier frame shiftable in said base frame and having walls of foraminous material to provide a 65 paper container, the opposite ends of said container being open, paper guides extending across the open ends of said container and adjustable toward and from each other, a shifter block carried by said paper container and reciprocal thereon, means to limit the extent of reciprocal movement between said block and container, a spring connecting said block to said container, said block having a coupling opening, and a block-shifting 70 arm entering said opening.

18. In an apparatus of the character described, in combination, a base frame composed of parallel, angle bars connected by cross-bars to form a skeleton, cradle-like frame, a cradle-like carrier frame shiftable in said base frame and having walls of foraminous material to provide a paper container, the opposite ends of said container being open, paper guides extending across the open ends of said container and adjustable 5 toward and from each other, a shifter block carried by said paper container and reciprocal thereon, means to limit the extent of reciprocal movement between said block and container, a spring connecting said block to said container, said block having a coupling opening, a block-shifting arm entering said opening, and a shiftable connecting rod along which said block-shifting arm is adjustable in the line of shift. 10
19. In an apparatus of the character described, in combination, a base frame composed of parallel, angle bars connected by cross-bars to form a skeleton, cradle-like frame, a cradle-like carrier frame shiftable in said base frame and having walls of foraminous material to provide 15 a paper container, the opposite ends of said container being open, paper guides extending across the open ends of said container and adjustable toward and from each other, a shifter block carried by said paper container and reciprocal thereon, means to limit the extent of reciprocal movement between said block and container, a spring connecting said block to said container, said block having a coupling opening, a block-shifting arm entering said opening, a shiftable 20 connecting rod along which said block-shifting arm is adjustable in the line of shift, and a paper table swinging from said container and having means for being supported by said connecting rod. 25
20. In an apparatus of the character described, in combination, a platen carriage, an arm fastened to and shifting with said carriage, a block connected to said arm so as to be shifted thereby, a paper carrier mounted for reciprocal movement, means connecting said block to said carrier and permitting of relative shifting between the two, and stops respectively on said block and said carrier and positioned for engagement with each other upon relative shifting movements of 30
- the block and carrier in opposite directions for limiting said opposite shifting movements. 35
21. In an apparatus of the character described, in combination, a platen carriage, an arm fastened to and shifting with said carriage, a block connected to said arm so as to be shifted thereby, a paper carrier mounted for reciprocal movement, means connecting said block to said carrier for longitudinal translatory relative shifting between the two, means for yieldingly resisting 10 relative shifting, and stops movable into engagement with each other for limiting said relative shifting. 15
22. A web carrier for writing machines including, in combination, a supporting frame, a plurality of tracks mounted on said frame, a carrier frame having rollers riding on said tracks, a driving block for said carrier, means including a pin and slot support mounting said block on said carrier for translatory movement substantially in the direction of shift of said carrier, means for limiting relative movements between said block and carrier, and driving connections connecting said block with a typewriter carriage. 20
23. In a web supporting carrier for typewriting machines, in combination, a supporting frame, a plurality of tracks mounted on said frame, two of said tracks being in different vertical and horizontal planes, a web carrier disposed intermediate said tracks and being suspended therebetween, 25 said carrier having supporting rollers riding respectively on said tracks and having its bottom portion depending below the level of both of said tracks and flexible driving connections between said carrier and the platen carriage of a type-writing machine. 30
24. In a web supporting carrier for typewriting machines, in combination, a supporting frame, means for attaching said frame to a typewriting machine, two tracks mounted on said 40 frame and disposed in different horizontal and vertical planes, a paper carrier, rollers secured at diagonally opposite edges of said carrier and riding upon said tracks for shifting movement therealong, and flexible driving connections between 45 said carrier and the platen carriage of the typewriting machine.

CHARLES WILLIS LARKIN.
